BOND BOX

Eldon C. Higgins, Cedar Rapids, Iowa, assignor to Lefebvre Corporation, Cedar Rapids, Iowa, a corporation of Iowa

Filed July 31, 1967, Ser. No. 8,062

Term of patent 14 years

U.S. Cl. D69—1
Int. Cl. D29—99

FIG 1

FIG 4

FIG. 1 is a perspective view of a bond box showing my new design;

FIG. 2 is a front elevational view thereof;

FIG. 3 is a fragmentary cross-sectional view taken on line 3—3 of FIG. 2; and

FIG. 4 is a fragmentary bottom plan view thereof.

The dominant features of my design reside in the portions shown in full lines.

I claim:

The ornamental design for a bond box, substantially as shown and described.
